THERAPEUTIC LAMP

Norris E. Goodrich, Battle Creek, Mich., assignor
to Battle Creek Equipment Company, Battle
Creek, Mich.

Application July 2, 1937, Serial No. 151,709

8 Claims. (Cl. 250—85)

The present invention relates to therapeutic lamps, and particularly to those lamps which have elements for producing ultra-violet and infra-red rays.

Natural sunlight consists of infra-red, visible, and ultra-violet rays, the use of the combination of all of which results in the well-known benefits of sunlight. Ultra-violet rays are short wave length rays known as actinic or chemical rays. Infra-red rays, on the other hand, are long wave length deep-penetrating heat rays. Ultra-violet rays alter the blood chemistry with resulting stimulation of metabolism, increase the vitamin content of the body, make vitamins more active, increase resistance to disease, and give new energy and strength. Infra-red rays cause dilation of the blood vessels, improve nutrition, relieve congestion and pain, and make the ultra-violet rays more effective by bringing the blood to the surface capillaries where the short wave length ultra-violet rays influence it advantageously. The presence of sufficient infra-red rays further makes possible the application of larger amounts of ultra-violet rays without destructive action on the tissues, and at the same time produces, in conjunction with the ultra-violet rays, bodily reactions and erythema like natural sunlight.

In Patent No. 1,735,679 issued to me November 12, 1929, I described a therapeutic lamp having a carbon arc for producing ultra-violet rays. A resistance was placed in series with the carbon arc to reduce the voltage, and at the same time to produce some heat. This apparatus involved the use of a segmental guard to catch and retain debris falling from the arc, and also utilized a large opening in the top of the reflector for ventilation purposes. My present invention has been devised to still further advance the art in this field and to produce a lamp which is a marked improvement over the therapeutic lamps heretofore placed on the market.

Accordingly, among the objects of the present invention is the provision of a therapeutic lamp adapted to supply both infra-red and ultra-violet rays, and to deliver them in balanced amounts when supplied together.

Another object is to provide a therapeutic lamp with a double, air-cooled reflector.

Another object is to provide a therapeutic lamp utilizing a bulb for producing ultra-violet rays.

Another object is to provide means for air-cooling the socket of the ultra-violet ray producing bulb.

Another object is to provide a therapeutic lamp

which utilizes Monel metal or metal-plated parts adapted to resist electric corrosion at the electric contact points of the ultra-violet ray bulb and infra-red ray units.

A further object is to provide a double wire 5 terminal connection for the end of each of the infra-red units.

A still further object is to provide means for adjusting the height of the lamp head above the floor, together with a special arm pivot for tilting the lamp head.

Further objects and advantages will appear as the description proceeds.

To the accomplishment of the foregoing and related ends, the invention, then, consists of the 15 means hereinafter fully described and particularly pointed out in the claims, the annexed drawing and the following description setting forth in detail certain means for carrying out the invention, such disclosed means illustrating, 20 however, but several of various ways in which the principle of the invention may be used.

In said annexed drawing:

Figure 1 is a front assembly view of one form 25 of the invention.

Figure 2 is a vertical section through the head of the lamp shown in Figure 1, but with the reflector rotated 45 degrees.

Figure 3 is a front view of a modified lamp head.

Figure 4 is a side view of one of the infra-red units.

Figure 5 is a partial section through the lamp head mounting on the vertical standard or pedestal extension.

Figure 6 is an edge view of the pivot for the lamp head.

Figure 7 is a typical wiring diagram for the lamp shown in Figure 1.

Figure 8 is a wiring diagram for a modified 40 form of lamp.

Referring more particularly to the drawing, Figure 1, as supplemented by Figure 5, shows one type of assembly which permits the lamp head to be slid up and down, as well as tilted forward and back. The lamp in this form has a base 1, and may, if desired, be provided with castors 2. On base 1 is provided a suitable ventilated housing 3 for a transformer 4. A switch mechanism 37 for the ultra-violet and infra-red ray units may 45 be installed at any convenient point, for instance, at the top of housing 3. Directly mounted over housing 3 is a tubular pedestal 5 with top cap 6 carrying pedestal extension 7. A suitable opening 8 is provided in top cap 6 to permit the pas- 55

sage of a wire cable from the bottom portion of the lamp through pedestal 5 to the units in the lamp head 9.

The lamp head 9 is mounted on pedestal extension 7 by means of a sliding arm 10 (Figure 5). For purposes of appearance, it is normally desirable to nickel or chrome plate pedestal extension 7, and in order to substantially avoid marring same in use, sliding arm 10 is provided with a fiber block 11. A screw member 12, preferably provided with a knob end, is adapted to threadedly engage a threaded opening in the back face of sliding arm 10 in manner such that when screw 12 is tightened, it will force fiber block 11 against the side of pedestal extension 7 to frictionally hold the head mechanism in place.

In order to permit the lamp head to be tilted forward and back, a pivot joint is provided between sliding arm 10 and head mounting arm 13 (Figures 5 and 6). Arm 13 is preferably made of hollow construction to permit the wire cable to pass therethrough into lamp head 9. This minimizes chafing and shorting of the cable in use. On opposite sides of the end of sliding arm 10 are provided flexible metal plates 14, which may be fastened in conventional manner as by welding or riveting to sliding arm 10. The head mounting arm 13 and metal plates 14 are provided with an opening through which bolt 15 may pass and form the pivot axis for the lamp head 9. The threaded end of bolt 15 is preferably provided with a hand-operated knob 16, which, for ease of operation, may be knurled. Between head mounting arm 13 and metal plates 14 are preferably provided fiber washers 17. These fiber washers 17 act to provide frictional resistance to pivoting of the lamp head 9 when hand-operated knob 16 is slightly loosened. In order to provide considerable latitude in the amount of frictional resistance to pivoting of lamp head 9, the bolt 15 may be provided with spring washers 18, one of which may be placed under the head of bolt 15, and another, if desired, under hand-operated knob 16. These spring washers will exert gripping tension on head mounting arm 13 even though hand-operated knob 16 is rotated a part turn for loosening purposes. In fact, if desired, hand-operated knob 16 may be left partially loosened, so that the lamp head 9 will be held in place, though it may be tilted forward or back at will.

Where lamp head 9 is constructed as shown in Figure 2, it is provided with reflector 19 and a cover housing 20. This type of construction provides an air space between reflector 19 and cover housing 20 with annular front opening which aids in air-cooling the mechanism, including the socket 21 for the ultra-violet ray bulb 22. This not only has the advantage of causing the socket 21 to have a longer life, but keeps the cover housing 20 relatively cool to the touch and permits it to be painted in various colors without danger of the paint burning therefrom. The back of the lamp head 9 is in the form of a cap 23, with ventilated sides, mounted on head mounting arm 13. A T-shaped member 24 fastened to cap 23 acts as the mounting for socket 21 which is preferably fastened thereto by means of screws having a spring washer or the equivalent under the head of each. The forward end of cap 23 is provided with a bell-shaped portion 25 and posts 26. When the cover housing 20 is placed up against the ends of posts 26 as shown, there is an annular ventilation opening between the bell-shaped portion 25 of the cap 23 and the

back face of cover housing 20. The latter is fastened by means of screws to posts 26, but before these screws are inserted, a cage 27 is set in place and the screws passed through suitable openings in its base to threadedly fasten it and the cover housing 20 to the posts 26 of cap 23. Reflector 19 is fastened to the forward end of cage 27 by means of suitable screws. While reflector 19 may be highly polished if desired, it is preferable to wire brush, or otherwise slightly roughen or satin finish the reflecting surface of same, so that the ultra-violet and infra-red rays will be reflected in diffused manner. This prevents "hot spots" or focus points of reflected rays which might cause serious burns.

In Figures 1 and 2, a reflector carrying 4 infra-red ray units 28 has been shown. There is no particular limitation to the use of 4 such units, and more or less may be used at the option of the manufacturer. Where a cheaper lamp is desired, 2 infra-red ray units 28a may be used in the lamp head, for instance, as is shown in Figure 3. These units, if desired, may be mounted on an elevated, independent, polished reflector piece 29 which is curved and tilted so as to face forward and down in manner such that its line of reflection will cross the axis of the main reflector 19a approximately two feet in front of the lamp head, a convenient distance from the lamp for the patient when taking a treatment. This reflector piece 29 also acts to prevent main reflector 19a from getting excessively hot at this point, and at the same time supplements the infra-red ray reflection of the main reflector 19a. The lamp shown in Figure 3 may be so constructed as to omit cover housing 20, and, in this case, the back face of reflector 19a is preferably nickel or chrome plated. Under these circumstances, cap 23 would be modified to extend for mounting directly on the back of main reflector 19a. This changed form of cap 23 has not been illustrated, since it is merely an appearance detail which is not one of the elements of the invention.

The infra-red unit 28 may be of various shapes, but one that is relatively easy to construct and wire is of the cylindrical shape shown in Figure 4. The infra-red unit consists of a grooved insulating core 30 with a lengthwise axial passage-way for the reception of a threaded rod with head, for instance, a cap screw or bolt 31. To withstand heat and burning, it is preferable to make the bolt out of a metal or alloy which is highly resistant to corrosion from heat at temperatures up to dull red, for instance, nickel alloys such as Monel or nichrome. The body of insulating core 30, for convenience, is provided with two openings therethrough at each end for use in threading and anchoring the resistance element 32 which is preferably in the form of nichrome wire. The upper end of the resistance element 32 is preferably double at the point of anchoring under the head of bolt 31. The doubling may be accomplished by turning the resistance wire 32 back on itself and then twisting, or a separate piece of wire may be used in equivalent manner. In preferred construction, the doubled end is sufficiently long to thread through the openings in the insulator as shown in Figure 4. The doubling of the wire at this point avoids burning in two of the resistance element, a thing which commonly occurs with a single wire if same happens to be nicked where it is bent around the terminal in assembling the infra-red ray unit. A further factor involved in the failure of a single wire at this point may be

the expansion of the parts of the infra-red ray unit under conditions of use, coupled with the high temperature of the resistance element 32. End 32a of the resistance element 32 may also be doubled in like manner to minimize danger of burning at the terminal. The lower end of the insulating core 30 is preferably provided with a projection 33 similar to a bushing and which is preferably slightly lower than the reflector is thick. The holes in the reflector 19 adapted to receive the infra-red ray units 28 are made of a size to receive projection 33. After the infra-red ray units 28 have been tightened into place, this projection 33 acts to prevent side slippage of the unit and shorting of bolt 31 on the reflector 19. Behind the reflector 19 at each infra-red ray unit is an insulating block 34 on which connections from infra-red ray unit to infra-red ray unit and to the source of current are made. Where the back face of this block 34 is hollowed out next to the reflector at the opening therethrough, projection 33 on insulating core 30 may be made correspondingly longer without interfering with the tight gripping of reflector 19 between infra-red ray element 28 and insulating block 34. A small insulating bushing 35 is used to insulate the end 32a of resistor element 32 where it passes through the reflector to the connection on the back of insulating block 34.

Where ordinary iron, steel, brass, or the like is used for the bolt and washers of the infra-red ray unit and socket for the ultra-violet ray bulb, it gradually disintegrates due to heat and electric corrosion, which appears to be, or at least is similar to electrolytic decomposition. To maintain a good connection which will be practically non-corrodable under conditions of use, it is preferable to use heat and electric corrosion resisting washers 36 for gripping the end of resistor element 32 under the head of bolt 31. These washers may be made of Monel metal, nichrome, or may be made of other corrosion resisting metal, or, if desired, may be nickel or chrome plated. The metal portion of the ultra-violet bulb socket in contact with the base of the bulb is also preferably made of corrosion-resisting metal, and one of the simplest ways of accomplishing this is to nickel plate the metal parts of the socket.

In Figure 7 is shown a typical wiring diagram for the therapeutic lamp shown in Figure 1. This hook-up, it will be noted, uses transformer 4, preferably of the auto transformer type, for supplying power to the ultra-violet ray bulb 22. The four infra-red ray units 28 are hooked in series with themselves directly to the line voltage through a separate switch. Under these conditions, the ultra-violet ray bulb 22 and infra-red ray units 28 are connected in parallel with each other. One of the various forms of ultra-violet ray bulbs 22 that may be used for this purpose is known to the trade as the General Electric S-1 bulb. This bulb has a coiled tungsten filament, two tungsten arc electrodes, and a pool of mercury all incased in a special glass tube. When the switch is closed for operating the ultra-violet ray bulb, the tungsten filament lights up and causes some of the mercury to vaporize, whereupon an arc forms between the two electrodes and emits rays which are rich in ultra-violet.

A modified form of wiring diagram is shown in Figure 8. The ultra-violet ray bulb and infra-red ray units here are operated in parallel through a single switch. This requires that both

the ultra-violet ray bulb and the infra-red ray units be operated together or else the infra-red ray units operated alone by screwing the ultra-violet ray bulb out sufficiently to break contact. The wiring shown in this diagram is particularly well adapted for use in connection with lamp head 9a of Figure 3. A three wire cable is all that is required to carry current to the ultra-violet ray and infra-red ray units in the lamp head when wired according to the diagrams shown in Figures 7 and 8.

Where the lamp, as shown in Figure 3, has two infra-red ray units, a convenient size for these is such that when operated in series, they will draw a load of 250 watts. Where four infra-red ray units are used, as shown in Figure 1, a convenient size for these units is such that when all four are connected in series, they will draw a total load of 500 watts. A convenient size of ultra-violet ray bulb, such as the General Electric S-1, will draw a load of 500 watts. These ultra-violet ray bulbs not only produce ultra-violet rays in the usable range of wave length (2600-3100 angstroms), but also a small amount of infra-red rays of the penetrating type (6500-14,000 angstroms). The ultra-violet ray bulb, accordingly, may be used alone for therapeutic treatments, but due to its low infra-red ray production, a more balanced combination of therapeutic rays is attained by the additional use of one or more infra-red ray elements, as described above. When using the combination of the S-1 ultra-violet ray bulb and four infra-red ray elements as shown in Figure 1, the rays emitted are not only several times stronger in ultra-violet rays than mountain sunlight at noon, but they are also fortified with additional infra-red rays of the penetrating type, thus increasing the therapeutic qualities of the rays delivered.

Other modes of applying the principle of my invention may be employed instead of those explained, change being made as regards the mechanism herein disclosed, provided the means stated by any of the following claims or the equivalent of such stated means be employed.

I therefore particularly point out and distinctly claim as my invention:

1. An irradiating device comprising in combination, a cap, a socket mounted in said cap and adapted to receive the connecting end of an ultra-violet ray bulb therein, means for ventilating said cap and cooling said socket, a reflector, means for joining said reflector to said cap, and a plurality of infra-red ray emitting means separately mounted on the inner face of said reflector.

2. An irradiating device comprising in combination, a cap, a socket mounted in said cap and adapted to receive the connecting end of an ultra-violet ray bulb therein, means for ventilating said cap and cooling said socket, a reflector, means for joining said reflector to said cap, a plurality of separate unit means within said reflector for emitting infra-red rays, each of said infra-red ray emitting units comprising an insulator having wound and anchored thereon a suitable metal wire resistance element, one end of said insulator having a bushing-like projection fitting a suitable opening in the reflector, a bolt passing through a suitable opening in said insulator, an insulating block back of the reflector and adapted to have the end of said bolt pass therethrough, means for tightening said bolt so as to fasten said insulator and insulating block in place, said bolt also being electrically connected

to the outer end of said wire resistance element, a separate small insulator with opening therethrough mounted in an opening through said reflector adjacent the opening therethrough for said first named insulator, the end of said wire resistance element adjacent the reflector passing through said separate small insulator, and means for connecting said ultra-violet and infra-red ray emitting units to a suitable source of electricity.

3. An irradiating device comprising in combination, a cap, a socket mounted in said cap, a cover housing mounted on said cap, a cage mounted in said cover housing, a reflector mounted on said cage within said cover housing in manner such that there is an air cooling and ventilating space between said reflector and cover housing to cool the former and to retard flow of heat from the former to the latter under operating conditions, an ultra-violet bulb removably mounted in said socket and passing through said cover housing and reflector so that the ray emitter portion of said bulb is within said reflector, and separate means within said reflector for emitting infra-red rays.

4. An irradiating device comprising in combination, a cover housing, a cap mounted on the back of said cover housing, a socket mounted in said cap, means for ventilating said cap and cooling said socket, a cage mounted in said cover housing on the opposite side thereof from said cap, a reflector mounted on said cage within said cover housing so as to be spaced therefrom in manner permitting air-flow between said reflector and cover housing to cool the former and retard flow of heat from the former to the latter under operating conditions, an ultra-violet bulb removably mounted in said socket and passing through said cover housing and reflector so that the ray emitter portion of said bulb is within said reflector, and a plurality of separate units for emitting infra-red rays, said units being separately mounted on said reflector and within the reflecting portion thereof.

5. An irradiating device comprising in combination, a cover housing, a cap mounted on the back of said cover housing, a socket mounted in said cap, means for ventilating said cap and cooling said socket, a cage mounted in said cover housing on the opposite side thereof from said cap, a reflector mounted on said cage within said cover housing so as to be spaced therefrom in manner permitting air-flow therebetween for cooling purposes, an ultra-violet bulb removably mounted in said socket and passing through said cover housing and reflector so that the ray emitter portion of said bulb is within said reflector, a plurality of separate units for emitting infra-red rays, each of said units being individually supported by said reflector and mounted within same adjacent the outer edge thereof, each unit being formed from an insulator having one end of a reduced size adapted to pass through a suitable opening in said reflector, a longitudinal passageway through said insulator adapted to receive a bolt, an insulating block back of said reflector and adapted to have said bolt pass therethrough so that when the bolt is suitably tightened the insulator and insulating block will grip the reflector therebetween while holding said bolt out of contact therewith, a resistance element wound on said insulator, the outer end of said resistance element being doubled back and the end of the doubled portion placed under the head of said bolt so that same acts as a conduc-

tor of electricity, and means for electrically connecting said ultra-violet bulb and infra-red ray emitting units to a suitable source of electricity.

6. In an irradiating device, the combination of a cover housing, a cap mounted on the back of said cover housing, said cap being provided with ventilation openings and means for holding the edge of same spaced from the back of the cover housing so as to further facilitate ventilation, a socket mounted in said cap and adapted to receive the connecting end of an ultra-violet bulb, a cage mounted in said cover housing on the opposite side thereof from said cap, a reflector mounted on said cage within said cover housing so as to be spaced therefrom in manner permitting air-flow therebetween for cooling purposes, a plurality of separate units for emitting infra-red rays, each of said units being individually supported by said reflector and mounted within same adjacent the outer edge thereof, each unit being formed from an insulator having one end of a reduced size adapted to pass through a suitable opening in said reflector, a longitudinal passageway through said insulator, a heat resisting bolt adapted to pass through said passageway, an insulating block back of said reflector and adapted to have said bolt pass therethrough so that when the bolt is suitably tightened the insulator and insulating block will grip the reflector therebetween while holding said bolt out of contact therewith, and a resistance element wound on said insulator and anchored by threading through suitable openings in the ends thereof, at least the outer end of said resistance element being doubled back for threading double through said openings and wrapping around said bolt under the head portion thereof so that said bolt becomes part of the electric circuit.

7. In a therapeutic lamp, the combination of a cover housing, a cap mounted on the back of said cover housing, a socket mounted in said cap, means for ventilating said cap and cooling said socket, a cage mounted in said cover housing on the opposite side thereof from said cap, a reflector mounted on said cage within said cover housing so as to be spaced therefrom in manner permitting air-flow therebetween for cooling purposes, an ultra-violet bulb removably mounted in said socket and passing through said cover housing and reflector so that the ray emitter portion of said bulb is within said reflector, separate units for emitting infra-red rays, said units being mounted on said reflector and within the reflecting portion thereof, supporting means for said lamp comprising a stand, a vertically slid able arm mounted on said stand, means for gripping said slid able arm on said stand at various locations, a reflector assembly supporting arm, a pivot connection between said slid able arm and reflector assembly supporting arm for permitting the reflector assembly to be moved to various positions ranging from vertical to horizontal, means for maintaining the reflector assembly in any such position, and means for electrically connecting said ultra-violet bulb and infra-red ray emitting units to a suitable source of electricity.

8. In a therapeutic lamp, the combination of a cover housing, a cap mounted on the back of said cover housing, a socket mounted in said cap, means for ventilating said cap and cooling said socket, a cage mounted in said cover housing on the opposite side thereof from said cap, a reflector mounted on said cage within said cover housing so as to be spaced therefrom in manner permitting air-flow therebetween for cooling pur-

poses, an ultra-violet bulb removably mounted in said socket and passing through said cover housing and reflector so that the ray emitter portion of said bulb is within said reflector, a plurality of separate units for emitting infra-red rays, each of said units being supported by said reflector and mounted within same adjacent the outer edge thereof, each unit being formed from an insulator having one end of a reduced size adapted to pass through a suitable opening in said reflector, a longitudinal passageway through said insulator adapted to receive an electrical corrosion and heat resisting bolt, an insulating block back of said reflector and adapted to have said bolt pass therethrough so that when the bolt is suitably tightened the insulator and insulating block will grip the reflector therebetween while holding said bolt out of contact therewith, a resistance element wound on said insulator, the outer end of said resistance element being doubled back and twisted and the end of such doubled portion placed under the head of said bolt so that same acts as a conductor of electricity, the other end of said resistance element also being doubled and twisted for a considerable distance from

its point of joinder to a suitable source of electricity, supporting means for said lamp assembly comprising a stand, a slidable arm mounted on said stand and provided with a fiber member therein in slidable gripping contact with the side 5 of said stand, means for gripping said fiber member against the side of said stand to hold said slidable arm in fixed position, a reflector assembly supporting arm, a pivot connection between said slidable arm and reflector assembly supporting 10 arm for permitting the reflector assembly to be moved to various positions ranging from vertical to horizontal, said pivot comprising two flexible metal plates attached to one of said arms, openings through said flexible metal plates and the 15 other arm for the reception of a pivot bolt, fiber washers on each side of said arm and between said flexible metal plates, a threaded member for engaging said bolt to permit controlled relative movement of said arms about said pivot, and 20 means for electrically connecting said ultra-violet bulb and infra-red ray emitting units to a suitable source of electricity.

NORRIS E. GOODRICH. 25
